EGG CARTON

Joseph Auguste Raymond Grenier, Montreal,
Quebec, Canada

Application June 23, 1952, Serial No. 295,065

2 Claims. (Cl. 229—7)

1

The present invention pertains to a novel egg carton, although it is applicable to containers of similar objects and is to be understood as having such scope.

The principal object of the invention is to provide a carton that permits easy and safe removal of the eggs or other objects therefrom. An egg to be removed from a standard carton can be grasped only lightly at its upper end. Consequently, in being lifted out of the carton, it often slips from the fingers of the user and breaks against the floor or table. This difficulty is overcome by the present invention.

Another object of the invention is to provide a simple and inexpensive modification of standard cartons to accomplish the purpose set forth.

In the accomplishment of these objects, the usual compartmented egg carton is formed with an aperture in the bottom of each compartment. Each aperture is such size as to receive a finger tip of the user.

A liner is fitted over the bottom of the carton, under the partitions that form the compartments. In the liner are formed flaps over the respective apertures. The eggs rest on these flaps. To remove an egg the user pushes a flap by a finger passed through the corresponding aperture, thereby lifting the egg sufficiently out of the carton so that it may be firmly grasped.

The invention is fully disclosed by way of example in the following description and in the accompanying drawings in which:

Figure 1 is a perspective view of the carton, showing the bottom thereof;

Figure 2 is a section on the line 2—2 of Figure 1;

Figure 3 is a similar section showing the use of the invention;

Figure 4 is a perspective view of the bottom liner; and

Figure 5 is a plan section in different planes.

Reference to these views will now be made by use of like characters which are employed to designate corresponding parts throughout.

In several of the figures is shown a conventional egg carton 1 made of suitable material and having the usual cover 2 and tuck-in flap 3. The interior of the carton is divided by longitudinal partitions 4 and transverse partitions 5 to form compartments or cubicles 6, each of a size to receive an egg 7.

The bottom 8 of the carton is formed with an aperture 9 at each compartment. Each aperture is of such size as to receive a human finger 10 for a purpose that will presently be described.

On the bottom 8 of the carton and beneath

the partitions 4, 5 is laid a false bottom or liner 11. This member is formed with flaps 12 over the respective apertures 9. Each flap is preferably rectangular and is formed by cutting through the member 11 on the sides at 13 and leaving the remaining side intact or, if desired, scored at 14.

The use of the device is shown in Figure 3. Ordinarily it is somewhat awkward and difficult to lift an egg out of its compartment. The user often fails to get a good grip on the egg and it falls from the fingers after being lifted out of the carton. This difficulty is avoided herein by merely inserting the finger 10 in the aperture 9 beneath the selected egg, raising the flap 12 and the egg with it whereupon a firm grip may be taken on the egg. The apertures 9 are smaller than the flaps, so that the bottom 8 is not weakened excessively; and the flaps are nearly as large as the bottoms of the respective compartments for effective operation.

Although a specific embodiment of the invention has been illustrated and described, it will be understood that various alterations in the details of construction may be made without departing from the scope of the invention as indicated by the appended claims.

What I claim is:

1. In an egg carton having a bottom and partitions therein forming egg compartments, said bottom having a finger aperture at each compartment, a liner laid on said bottom beneath said partitions, and flaps cut out of said liner at the respective apertures, said flaps being of larger area than the respective apertures, and of somewhat smaller area than the bottoms of the respective compartments.

2. In an egg carton having a bottom and partitions therein forming egg compartments, said bottom having a finger aperture at each compartment, a liner laid on said bottom beneath said partitions, and flaps cut out of said liner at the respective apertures, each flap being integral with said liner at one of its edges, said flaps being of larger area than the respective apertures, and of somewhat smaller area than the bottoms of the respective compartments.

JOSEPH AUGUSTE RAYMOND
GRENIER.
